UNITED STATES PATENT OFFICE

WALTER PRUSSING, OF BROOKLYN, NEW YORK, ASSIGNOR TO VICTOR METAL PRODUCTS CORPORATION, OF BROOKLYN, NEW YORK, A CORPORATION OF NEW YORK

DIE FOR EXTRUDING COLLAPSIBLE TUBES

Application filed February 4, 1931. Serial No. 513,293.

This invention relates to the die sets used in the extrusion of soft metal blanks into collapsible tubes, such as those used for tooth-paste, shaving cream, and the like, and to the art of making dies for prolonging the operating life of such dies.

In the process of making collapsible tubes, a disc either flat or dished, is fed to a female die which is held on the table or bed in a suitable press, and an elongated male die is then brought down upon the disc, thereby squeezing the disc into a conical recess in the female die and causing the metal of the disc to squirt or flow with great rapidity in the direction of the pressure put thereupon by the male die, the metal thinning out during this operation, whereby the thin wall of the tube is extruded and the tube is formed. The outermost diameter is determined by the diameter of the opening in the female die just above the conical recess and the innermost diameter of the tube is determined by the diameter of the lowermost part of the cylindrical portion of the male die.

Great pressure is exerted upon the female die during the extruding operation. Attempts have heretofore been made, therefore, to increase the life of the female die by hardening it about the forming recess thereof. Such attempts have been unsatisfactory, because the die must be so thick to resist the pressure, that it cannot be properly hardened to a sufficient distance outwardly of the recess. The female die, in such cases, cannot resist the great pressure exerted thereon, and frequently splits. It must consequently be replaced from time to time, with greater or less frequency depending upon the efficiency with which it has been hardened.

It is advisable, in such female dies, to maintain the outermost portion thereof unhardened or comparatively soft and elastic, so that the die may give way sufficiently without breaking to absorb and resist the pressure put thereon. The accurate conditioning of the hardened operative portion in connection with a comparatively soft outer portion has heretofore been impossible of attainment, particularly, because the die has customarily been made of a single piece.

My invention therefore contemplates the provision of a female die made of two or more parts. The outermost part which is not subjected to wear, is permanent and unhardened, and designed to be used over and over, irrespective of possible breakage of the other parts while the innermost or operative portion or portions on which the wear is concentrated, is hardened throughout and is so designed as to be replaceable when damaged or worn out. My invention further contemplates the provision of a simple and efficient connection for holding the die parts together while permitting replacement thereof. My invention further contemplates the provision of a separable forming ring cooperating with the remainder of the female die for prolonging the life of the die and for controlling the outer diameter of the tube formed by the extruding process. My invention also contemplates a process for making and using dies to prolong the life of the ring and of the die in spite of excessive wear thereof, by compensating for the enlargement of the ring due to wear and due to the lapping or re-grinding processes which may slightly increase its diameter. My invention further contemplates the provision of simple and efficient means for removably holding the die parts in place.

The various objects of my invention will be clear from the description which follows, and from the drawings, in which,

Fig. 1 is a diagrammatic elevation of a typical tube extruding press in which my improved dies are designed to be used.

Fig. 2 is a top plan view of the female die as it appears assembled on the table or bed of the press.

Fig. 3 is a front elevation and partial section of the same, showing the male die withdrawn from the female die and showing the forming ring sprung or deformed after wear to compensate for its increased diameter.

Fig. 4 is a vertical section of part of the die and of the guard ring, showing the diameter controlling or forming ring when new or unworn and in its normal position.

Fig. 5 is a top plan view of a modified form of the bottom part of the female die, and

100

Fig. 6 is a partial front elevation and partial section of the same, showing the male die partly withdrawn.

In that practical embodiment of my invention which I have illustrated by way of example, the press 10 comprises the frame 11 provided with the toggle 12 which operates the cross head 13 carrying the male die and by means of which the male die 14 is vertically 10 reciprocated. The female die, designated generally by the numeral 15, is suitably held removably on the table 16 of the press, as will be more fully described hereinafter.

As the male die 14 is reciprocated into and 15 out of the female die, the slugs or blanks which may be flat or dished, are suitably fed to the die horizontally in a manner which need not be here described, and the blanks are squeezed and extruded into tubes, which 20 are pulled out of the female die by the male die, and then removed from the male die. The female die may be constructed in several ways, but in any case, it consists of two or more parts.

25 Referring now to Figs. 5 and 6, the male die 14 comprises the usual neck 20 which forms the perforated neck of the tube, the conical portion 21 which forms the conical part of the tube connecting the neck with 30 the cylindrical tube body, and the substantially cylindrical portion 22 joined by a slightly concavely curved surface 23 to the conical portion. It will be understood that the diameter of the corner or edge at the 35 juncture of the portions 21 and 22 controls the inner diameter of the tube formed by the dies. As shown, the female die bottom comprises the outer ring 24 provided with a slightly tapered or conical opening 25, and 40 includes the member 26. Said ring 24 is preferably made of steel which is not hardened. The ring therefore remains comparatively soft and elastic and consequently, under the pressure of the extruding operation, 45 gives slightly or absorbs the pressure and hence may last indefinitely. The wear and stress upon the die is, however, taken up by the hardened inner or center member 26 of the die set. The member 26 is provided with 50 an outermost conical surface 27 having the same taper as the inner surface of the ring 24 surrounding the opening 25. Said member 26 is forced into the opening 25 and into pressed contact with the surface surrounding 55 the opening 25, under suitable pressure.

I have found that a pressure of about 40 tons is sufficient to maintain the die parts 24 and 26 in their proper positions when assembled. I have further found that a taper of about two degrees on the conical surfaces 25 and 27 forms a quite satisfactory angle, making the proper assembly of the die parts possible, and making it also possible to disassemble said parts should it be 60 required to do so.

The inner hardened die member 26 is provided with a cylindrical opening 28, in which operates the knockout pin 30, as will be more fully described hereinafter, said pin in its uppermost position, determining the length 70 of the neck of the finished tube. The member 26 is further provided with a conical recess 29 for shaping the conical portion of the collapsible tube, in cooperation with the conical surface 21 of the male die. It will be understood that the lowermost limit of the stroke of the cross head is predetermined to produce a conical portion on the resulting tube of the proper thickness. It will further be understood that as illustrated in Fig. 3, the die bottom 31 of one piece properly hardened about the forming recesses and openings may be used, if desired, instead of the two-piece die bottom shown in Figs. 5 and 6. One end of the recess 29 terminates at the upper surface of the die bottom, and the other end terminates at and communicates with the opening 28.

In order, however, to prolong the operative life of the die set, a separate and independent reversible and removable ring 32 is used to determine the outer diameter of the extruded tube and therefore to determine the thickness of the body of said tube.

Said ring is provided with a normally flat upper surface 33, parallel to the similar lower surface 34, and is further provided with a preferably cylindrical opening 35 surrounded by the wall 36. It will be understood that the corner or edge 37, at the juncture of the lower surface 34 and the wall 36, determines the outer diameter and thickness of the tube extruded by the dies. Said corner 37, therefore, is subjected to the pressure of the metal flowing thereby, and to greater wear than any other part of the ring 32. Ordinarily, it would become necessary to discard the ring after the wear at the corner 37 had reached such an amount as to fail to determine properly the diameter of the extruded tube. I have, however, provided a new process and means for enabling my new ring to be used even after the corner 37 has been worn to a considerable extent. Toward this end, the upper surfaces 17 and 19 and 40 of the die bottom ring 24 and member 26 and the die bottom 31 respectively, are bevelled downwardly and outwardly to a slight extent. The surfaces 17 and 19 are aligned with each other and inclined at the same angle to the horizontal, being separated by a recess as 18 to avoid unnecessary machining. Similarly, the under surface 41 of the guard ring 42 is bevelled or inclined at the same angle, to make it parallel to the surface 40.

When the corner 37 has become so worn that it fails to function properly, the ring 32 is reversed or turned upside down to bring the corner 38 into operative position. The

130

use of the ring 32 may then be continued even though it is maintained flat in the die set. When both corners 37 and 38 become so worn that the ring again fails to function properly, the ring is removed from the die set, and the surface 36 is ground or lapped to a sufficient extent to make it again cylindrical.

In practice, it is only necessary to remove about two thousandths of an inch for this purpose. The lapping operation, however, increases the diameter of the wall 36 to a slight extent. To reduce the corner 37 again to its proper diameter, the guard ring is drawn toward the die bottom in a manner soon to be explained, whereby the ring 32 is sprung, deformed or distorted to make it slightly convex upwardly owing to the pressure put thereon by the bevelled or inclined surfaces 41 and 40. By so bending, deforming or springing the ring 32, the wall 36 is changed from a cylindrical to a slightly conical surface and the diameter of the corner 37 becomes slightly lessened to a sufficient degree to allow the ring to function again for the proper control of the diameter of the extruded tube. This diameter can be adjusted as desired by tightening or loosening the nut 56. Similarly, when the corner 37 wears out again and becomes inoperative, the ring may be again reversed and similarly spring to bring the corner 38 into operative diameter controlling position. This operation may be repeated and the pressure exerted on the ring 32 increased from time to time to prolong the life of the ring, and of the dies to a substantial extent, particularly in connection with the replaceable hardened member 26.

The guard ring 42 is provided with an upper surface 43 serving as a guide for the entrance of a blank into the opening 44 thereof. To stop the horizontal movement of the blank and to align it for entrance into the die, a guard wall as 45 is provided, projecting above the surface 43. Said guard wall stops the horizontal advance or feed of the blank, so that the blank falls through the opening 44 and into the opening 35 of the ring 32, ready for the extruding operation.

To maintain the die bottom 31, the ring 32 and the guard ring 42 in their proper positions, and under the proper pressure, these parts are assembled upon a suitable bolster 50 suitably secured removably to the bed of the machine as by means of the nuts or bolts 51. An opening as 53 is provided in the bolster into which is inserted the projection 54 of the die bottom 31 or 26 to hold the die bottom against transverse movement.

Suitable means are provided for reciprocating the knockout pin 30 in the openings 53 and 28 which means need not be shown nor further described. Said pin serves to release the extruded tube from the female die

at the completion of the extruding operation. The bolster 50 is further provided with an externally threaded projection 55 engaged by the internally threaded nut 56. Said nut is provided with a shoulder 57 engaging the shoulder 58 of the guard ring and exerting downward pressure thereon to clamp the parts in place. It will be understood that the downward clamping pressure of the nut on said parts may be adjusted as may be found desirable, particularly, for the springing or deformation of the ring 32 when such springing is required. It will further be seen that by making the female die in separate pieces, the wearing parts may be replaced if damaged or worn, from time to time, or ground and reinserted or deformed as may be necessary to avoid replacement and to prolong the life of the die.

It will be seen that I have provided simple and efficient means, capable of withstanding hard wear and extremely durable even though used over long periods in connection with dies for extruding collapsible tubes. It will further be seen that the disadvantages of such dies heretofore pointed out have been overcome by means of my invention, and that I have produced a device well adapted to meet the severe requirements of practical use.

While I have shown and described certain specific embodiments of my invention, it will be understood that I do not intend to limit myself thereto but desire to claim my invention as broadly as may be permitted by the state of the prior art and the terms of the appended claims.

I claim:

1. In a die set for the extrusion of metal blanks into collapsible tubes, a female die comprising an outer resisting ring of unhardened metal having an inner conical surface surrounding an aperture in the ring, and a hardened metal member having a conical forming recess therein, and provided with an outer conical surface forced into engagement with the inner conical surface of the outer ring, the upper surface of said ring and of said member being inclined downwardly and outwardly, and a male die reciprocating to enter the conical recess to squeeze a blank against the conical recess of the member and to force the metal of the blank in the direction of the reciprocation of the male die and thereby to form a tubular wall about the male die.

2. In a die set for extruding comparatively soft metal blanks into collapsible tubes, a female die comprising a removable hardened steel center having a recess therein, an unhardened steel ring forced about the hardened center, and a reciprocatory male die cooperating with the recess of the hardened center to extrude the blank into a tube.

3. In a female die for the extrusion of com-

paratively soft metal discs into collapsible tubes, an outer ring of unhardened metal, and an inner member of hardened metal having a forming recess therein, and pressed into 5 forced engagement with the outer ring and removably held thereby.

4. In a female die for the extrusion of comparatively soft metal discs into collapsible tubes, an outer unhardened ring having 10 an inner conical surface surrounding an aperture therein, and a hardened inner die member forced into said aperture and against said surface and having a forming recess therein.

15. 5. In a female die for the extrusion of comparatively soft metal discs into collapsible tubes, an outer ring of unhardened metal, an inner die member having a forming recess therein pressed into forced engagement 20 with the outer ring and arranged coaxially thereof, the upper surfaces of said ring and said member being bevelled slightly downwardly and outwardly.

25. 6. In a die set for extruding blanks into collapsible tubes, a female die having a hardened center portion provided with a conical forming recess terminating at one end at the upper surface of the disc and terminating at its other end in a cylindrical opening, and 30 having a slightly conical outermost surface, and an outer unhardened ring more elastic than the center portion and having an inner conical surface of the same taper as the outermost surface of the center portion, the center portion and the ring being assembled 35 by pressure coaxially thereof to bring said conical surfaces into forced engagement, whereby the center portion may be forcibly removed from the ring when damaged, and 40 a new center portion inserted into the ring.

45. 7. In a die set for extruding blanks into collapsible tubes, a female die having a forming recess therein, a downwardly and outwardly bevelled upper surface on the female die, a reversible forming ring above the female die, said ring having normally flat ends and having an aperture therein arranged coaxially of the recess, the lowermost corner surrounding the aperture determining the 50 outer diameter of the tube formed from the blank, and means for distorting the forming ring to bring the normally flat lower surface thereof into contact with the bevelled upper surface of the female die and to thereby reduce the diameter of said corner, said means including an adjustable nut arranged to bring 55 pressure upon the ring in the direction of the axis of the aperture therein.

60. 8. In a die set for extruding blanks into collapsible tubes, a female die comprising an unhardened outer ring, a hardened inner die member held by the outer ring and having a forming recess therein, aligned and downwardly and outwardly bevelled upper surfaces on the ring and the die member, and a 65

forming ring on the female die adapted to be sprung convexly upwardly with its lower face in engagement with the bevelled surfaces of the female die to decrease the effective inner diameter of the forming ring. 70

9. In a die set for extruding blanks into collapsible tubes, a female die having a bevelled surface, a forming ring, and a nut for adjustably pressing the ring toward the bevelled surface to hold the ring thereagainst and to deform the ring for determining its effective inner diameter. 75

10. In a die set for extruding blanks into collapsible tubes, a reversible forming ring for determining the outer diameter of the tube extruded by the die set, and an adjustable member for deforming the ring by pressure thereon, and by varying the least innermost diameter thereof. 80

11. In a die set for extruding blanks into collapsible tubes, a reciprocatory male die for determining the innermost diameter of the extruded tube, a stationary cooperating female die having a bevelled upper surface, a forming ring for determining the outermost diameter of the tube, and a vertically adjustable member for putting pressure upon the ring to hold the ring on the female die and to deform the ring to vary the effective innermost diameter thereof after said diameter has become changed. 85

12. In a die set for extruding blanks into collapsible tubes, a female die having a bevelled upper surface, a guard ring having a similarly bevelled lower surface, a normally flat forming ring between said surfaces, and adjustable means for pressing the forming ring toward the female die to hold the forming ring in operative position, and to determine the effective innermost diameter of the forming ring. 90

13. In a die set for extruding blanks into collapsible tubes, a female die having a bevelled upper surface, a guard ring having a similarly bevelled lower surface, a normally flat reversible forming ring between said surfaces, and adjustable means for pressing the forming ring toward the female die to hold the forming ring in operative position and to determine the effective innermost diameter of the forming ring, said effective diameter being located at the juncture of the lowermost and innermost surfaces thereof and determining the outermost diameter of the tube, and a male die reciprocating into and out of the female die and determining the innermost diameter of the tube. 115

14. In a die set for extruding blanks into collapsible tubes, a female die having a central aperture therein, and having a coaxially arranged conical recess terminating at its upper end at the upper face of the die, and at its lower end joining the upper end of the aperture, an independent and reversible forming ring having an opening there- 120

through cooperating with said conical recess to determine the outermost diameter of the tube, and means for pressing said forming ring against the die, for retaining said die

5 and ring in operative position, and for controlling the shape of said ring, and thereby determining the diameter of the corner at the juncture of the lowermost surface of the ring and the wall of the opening therein.

10 15. In a die set for extruding blanks into collapsible tubes, a female die comprising an outer unhardened ring, part of the upper surface of the ring being inclined downwardly and outwardly, a hardened metal member

15 forcibly inserted into said ring and forcibly removable therefrom, said member having its upper surface aligned with the inclined upper portion of the ring, and having a conical recess therein having its greatest di-

20 ameter at said upper surface of the member, and a reversible and a deformable forming ring arranged on said die and cooperating therewith to determine the outermost diameter of the tube.

25 16. In a die set for extruding blanks into collapsible tubes, a female die having a conical recess therein terminating at the upper surface of the die, said upper surface being inclined slightly downwardly and outward-

30 ly, a guard ring for guiding blanks into the die, said guard ring having a similarly inclined lower surface, a reversible forming ring having normally flat upper and lower surfaces engaging the respective inclined sur-

35 faces of the guard ring and the die, and adapted to be distorted by the relative adjustment of the guard ring and the die to vary the effective innermost diameter of the forming ring.

40 17. In a die set for extruding blanks into collapsible tubes, a bolster having an opening therein, an externally threaded projection arranged coaxially of the opening, a nut internally threaded to engage said threaded

45 projection, and having an opening therein constricted at its upper end to form an internal shoulder, a female die having a conical uppermost recess, and a communicating cylindrical aperture therethrough, a projec-

50 tion on the lower face of the die inserted into the opening of the bolster, an independent reversible forming ring on the die, and a guard ring on the forming ring, the upper surface of the die and the lower surface of

55 the forming ring being parallel and inclined out of the horizontal, said guard ring having an outwardly projecting shoulder engaging the internal shoulder of the nut whereby rotation of the nut varies the pressure on the

60 forming ring, and whereby said forming ring may be distorted between the inclined faces of the guard ring and the die.

18. In a die set for extruding blanks into collapsible tubes, a female die having an in-

similarly inclined lower face, and a forming ring between the guard ring and the die, said forming ring having normally flat upper and lower surfaces.

19. The process of reducing the effective 70 diameter of the forming ring of a die after said diameter has been increased by wear, comprising lapping the forming ring to overcome the effects of wear, and to increase its innermost diameter, and finally putting 75 pressure on said ring to distort it sufficiently to reduce its innermost diameter to the required size.

20. In a die set for extruding blanks into collapsible tubes, a female die comprising 80 an outer unhardened steel ring having an inclined upper surface, a hardened inner steel die member forced into said ring and held thereby, and having a conical recess therein terminating at the upper surface of said member, said upper surface being inclined 85 similarly to and aligned with the upper surface of the outer ring, a guard ring having a projection for stopping horizontally fed blanks, and having an opening therein for 90 the reception of said blanks, said guard ring having a similarly inclined lower surface, a normally flat forming ring between the guard ring and the die, said forming ring having an opening therein for the reception of the blank falling through the guard ring, and means for varying the diameter of the lowermost part of said opening in the forming ring 95 comprising a member for forcing the guard ring toward the die and thereby distorting 100 the forming ring, and a reciprocating male die cooperating with the female die for determining the shape of the end of the tube and the innermost diameter thereof.
